UNITED STATES PATENT OFFICE.

OSCAR ZERK, OF CLEVELAND, OHIO, ASSIGNOR, BY MESNE ASSIGNMENTS, TO GEORGE W. BOWEN, OF AUBURN, NEW YORK.

PRIMING-CUP.

1,212,727.

Specification of Letters Patent. Patented Jan. 16, 1917.

Application filed April 3, 1913. Serial No. 758,551.

To all whom it may concern:

Be it known that I, OSCAR ZERK, a subject of the Emperor of Austria, residing at Cleveland, in the county of Cuyahoga and State of Ohio, have invented a certain new and useful Improvement in Priming-Cups, of which the following is a full, clear, and exact description, reference being had to the accompanying drawings.

10 The object of this invention is to provide a very simple and effective priming cup, for explosive engines, for example.

My priming cup provides a cup member adapted to be secured to the engine, a cap member screwing to the cup member, and a rod carried by the cap member and coöperating with an opening in the base of the cup to constitute a needle valve. Oil may be admitted through the top of the cap into the cup and then the rotation of the cap opens the valve to discharge such oil into the engine. A suitable spring detent device is provided between the cap and cup, whereby inadvertent displacement of the cap is prevented.

My invention is hereinafter more fully explained and its essential characteristics summarized in the claims.

In the drawings, Figure 1 is a side elevation of my priming cup; Fig. 2 is a vertical central section thereof; Fig. 3 is a plan; Fig. 4 is a cross section of the cap below its detent spring, looking upwardly; and Fig. 5 is a perspective of the detent spring shown.

35 As shown in the drawings, 10 represents the cup proper, which may be a body made of pressed metal, or otherwise formed, as desired. This cup has an angular exterior 11, below which is an externally threaded portion 12, and above the angular portion is a flaring portion 13, above which is a wall 14 with an external thread. A continuous chamber is provided by the various parts mentioned.

40 20 designates the cap. This has a vertical wall 21 provided with an internal screw thread 22 adapted to screw onto the threaded portion 14 of the cup. Suitable knurling 23 on the cylindrical portion of the cap provides convenient means for turning it.

45 20, in Figs. 2 and 4, indicates a rod carried by the cap coöperating with the base of the cavity in the cup to constitute a needle valve. This rod has its upper end 31 riveted or upset in the cap, so that it is rotated

by the cap. At its lower end it is formed conically, as shown at 32, and coöperates with a conical seat in the lower portion of the chamber 15 in the cup. Normally this conical point 32 rests snugly in its seat, so that the exit of oil through the opening 16 is prevented. Accordingly, the cup may be filled through the opening 24 in the cap, and thereafter the unscrewing rotation of the cap withdraws the rod 30 from its seat, allowing a measured quantity of oil to pass into the engine.

To effectively lock the cap to the cup and at the same time allow a sufficient force to rotate the cap as desired, I provide a very simple and effective spring detent mechanism, which I will now describe.

The valve rod 30 near its upper end has a collar 34. Surrounding the rod and clamped between this collar and the under face of the cap, is a spring 40 which may have the form shown in Figs. 2, 4 and 5. As there shown, the spring consists of a disk having the horse-shoe-shaped opening 41, to provide a spring ring 42 extending freely outside of the collar 34, this ring being bent downwardly at its farthest point, making a projection 43. This projection is adapted to coöperate with notches 17 in the upper edge of the wall of the base. The spring 40 normally maintains the projection in engagement with one of these notches, and thus locks the cap to the cup, but a suitable force applied to the cap forces the spring lock out of the notches and enables the cap to rotate. A suitable opening 45 in the spring disk 40 registers with the opening 24 in the cap and thus allows the passage of oil.

It will be seen that my priming cup is extremely simple in construction and is neat in appearance. It results in keeping the opening 16 normally tightly closed. Oil may be admitted whenever desired through the opening 24. When the cup is filled the backward rotation of the cap allows the contained oil to pass into the engine. Whenever desired, the cap with its rod may be removed entirely from the cup, and the latter used as a funnel for transmitting oil to the engine.

Having thus described my invention, what I claim is:

1. In a device of the character described, the combination of a cup having a cavity,

a cap threading on the cup and having a central rod secured thereto and coöperating with a seat at the base of the cavity in the cup, and a spring detent carried by the cap within the same and coacting with the cup, substantially as and for the purpose set forth.

2. In a device of the character described, the combination of a cup having a cavity 10 and having an external thread, a cap having a wall with an internal thread screwing onto the external thread, a central rod rigidly secured to the cap and coöperating with a seat at the base of the cavity in the cup, a washer-like spring surrounding the rod and having a downward projection, and notches in the upper edge of the cup with which such projection may coact.

3. In a device of the character described, 20 the combination of a cup having an external thread and a notched upper edge, a cap having a wall internally threaded and screwing onto the cup, a central rod rigidly secured to the cap and acting as a valve on a seat near the lower end of the cup, a spring within the cap surrounding the

rod, and rotatable therewith and clamped between a shoulder on the rod and the head of the cap, said spring having a downward projection coöperating with the notches in 30 the upper edge of the cup.

4. In a device of the character described, the combination of a cup having an external thread, a cap having a wall with an internal thread screwing onto the external 35 thread, a central rod having its upper end upset in the cap and coöperating at its lower end with a seat at the base of the chamber in the cup, a spring detent for locking the cap to the cup, comprising a 40 spring clamped by the rod to the head of the cap and rotatable therewith, said spring having a projection and there being notches in the upper edge of the cup with which such projection coöperates. 45

In testimony whereof, I hereunto affix my signature in the presence of two witnesses.

OSCAR ZERK.
